UNITED STATES PATENT OFFICE.

HERMAN C. PRIEBE, OF BLUE ISLAND, ILLINOIS.

DRAFT-GEAR

1,282,942.

Specification of Letters Patent. Patented Oct. 29, 1913.

Application filed July 22, 1913. Serial No. 246,180.

To all whom it may concern:

Be it known that I, HERMAN C. PRIEBE, citizen of the United States, residing at Blue Island, in the county of Cook and State of Illinois, have invented a certain new and useful Improvement in Draft-Gears, of which the following is a full, clear, concise and exact description.

My invention relates to draft gears of the type employing inner and outer followers actuated by couplers, rockers individual to the followers and movable thereby, and means, operating through said rockers, for resisting the approach of the followers toward each other. This motion resisting means is preferably in the form of spring mechanism, particularly where friction is not relied upon to resist the relative movement of the followers.

It is the object of my invention to improve the construction and arrangement of the component parts of the gear which have been named.

In practising my invention I employ at least two sets of interacting rockers, each set having one rocker individual to each follower and movable thereby. The rockers of each set interact through a floating roller structure, there being desirably one roller individual to each rocker. The rollers operate upon and are carried by a floating member that is included in the floating roller structure and which separates the rollers belonging to the different sets of rockers. The rockers are interposed between two motion resisting elements, each element being individual to a follower and in alinement with the other element and with both followers. The aforesaid floating member of the floating roller structure also preferably acts as a retaining block or member that prevents the rockers from falling out, which may happen in the event of breakage or distortion of the center sills and other parts of the under structure of the car. There are features respecting the preferred form of floating member which are claimed herein irrespective of the presence or absence of the rollers pertaining thereto.

I will explain my invention more fully by reference to the accompanying drawings showing the preferred embodiment thereof and in which Figure 1 is a sectional view taken generally on line 1—1 of Fig. 2; Fig.

2 is a sectional view taken generally on line 2—2 of Fig. 1; Fig. 3 is a sectional view on line 3—3 of Fig. 1; Fig. 4 is a sectional view on line 4—4 of Fig. 1; Fig. 5 is a view illustrating some of the elements appearing in Fig. 1 but in changed positions; Fig. 6 is a perspective view illustrating a follower and two rockers belonging to different sets and each individual to said follower; and Fig. 7 is a perspective view illustrating the floating block or member and two rollers of the roller structure.

Like parts are indicated by similar characters of reference throughout the different figures.

The coupler 1 has a coupler shank 2 to which the outer ends of a yoke 3 are secured by means of rivets or bolts 4. An outer follower 5 is engaged by the coupler butt 6 and is moved inwardly whenever the coupler is subject to sufficient pushing strain. The inner follower 7 is engaged by the inner end of the coupler yoke 3 and is movable outwardly when the coupler is subject to sufficient pulling strain. The extent to which the outer follower is movable outwardly is limited by the outer stops 8. The extent to which the inner follower 7 is movable inwardly is limited by the inner stops 9. All of the said stops are riveted against the center sills 10 that form a part of the under-frame structure of a car equipped with the draft gear. The followers 5 and 7 are in the nature of spring barrels which house the coöperating spring elements 11 and 12 of mechanism that is employed to resist the movement of either follower toward the other and to effect the return of the followers toward the stops respectively pertaining thereto.

One or more sets of rockers are disposed between the followers. I have illustrated two sets of rockers, each set including a rocker 13 individual to the outer follower 5 and a rocker 14 individual to the inner follower 7.

The outer follower 5 carries two seats or mountings 5¹, one for each rocker 13 to rock upon. The inner follower 7, similarly, carries two seats or mountings 7¹ one for each rocker 14 to rock upon. All of the rockers are of similar construction, the rockers of each set being symmetrically arranged. They interact preferably by being operated upon by the coiled springs 11, 12 of the mo-

tion resisting mechanism, these springs serving to oppose the relative movement of the followers by opposing the attendant follower effected rocking movement of the rockers. Each rocker has a part thereof which is in engagement with the seat provided upon the follower individual thereto curved to form a segment of a cylinder, the seat upon the follower engaged thereby being similarly curved. By this construction each rocker has an axis of rotation which is substantially fixed with respect to the follower individual thereto. Each rocker is preferably formed with a cavity for receiving the adjacent end of the corresponding spring, such a cavity being illustrated at 15 in Fig. 6. The aforesaid seats 5¹, 7¹ and the rockers engaging the same are desirably placed upright, in which event the follower 5 is provided with inner ledges 5² between which the rockers 13 are disposed and the follower 7 is provided with outer ledges 7² between which the rockers 14 are disposed, these ledges preventing the rockers from moving up and down materially.

The floating member 16 is hollow or box-like and sufficiently incloses the rockers to maintain them in assembly with each other and other portions of the gear in the event of breakage or distortion of the center sills or other parts of the under structure of the gear. Opposing portions of the rockers of the two sets project into the interior of the box-like hollow floating member 16 which is disposed transversely of the gear and between the center sills for this purpose. In order that this floating member 16 may also form a part of the floating roller structure I divide the floating member into two compartments by means of a partition 16¹ parallel with the open ends of the member and extending transversely of the gear. The rollers are desirably in the form of cylindrical segments 17 which have fulcra fixed with respect to the floating member 16, the central portions of these cylinder segments being rounded concentrically with the axes thereof and engaging the correspondingly rounded corners formed by the partitions 16¹ and the upright sides of the member 16. The rollers are thus upright and the axes thereof substantially fixed with respect to each other. The outer or areal faces of the rollers have rolling contact with the rockers as the followers are moved longitudinally of the gear with respect to each other. The rollers have tongues 18 which enter grooves 19 formed in the rockers, these tongues and grooves serving to maintain the rollers in their assembly with the floating member while at the same time permitting the rollers to roll upon the rockers. In the form of gear shown approach of either rocker toward the other is desirably resisted mainly by the action of the springs, there

preferably being no effective motion retarding friction although I do not wish to have the invention limited in this respect. The rockers of the two sets interact through the intermediation of the floating roller structure whereby the springs in both followers cooperate.

While I have herein shown and particularly described the preferred embodiment of my invention I do not wish to be limited to the precise details of construction shown as changes may readily be made without departing from the spirit of my invention, but having thus described my invention I claim as new and desire to secure by Letters Patent the following:

1. A draft gear including a coupler; inner and outer followers actuated thereby and movable each toward the other; springs, one individual to each follower, for resisting the approach of the followers toward each other; two interacting rockers, one rocker being individual to each follower and actuatable thereby, said rockers being interposed between and engaged by said springs; and a floating roller structure interposed between said rockers.

2. A draft gear including a coupler; inner and outer followers actuated thereby and movable each toward the other; motion resisting elements, one individual to each follower, for resisting the approach of the followers toward each other; two interacting rockers, one rocker being individual to each follower and actuatable thereby, said rockers being interposed between and engaged by said motion resisting elements; and a floating roller structure interposed between said rockers.

3. A draft gear including a coupler; inner and outer followers actuated thereby and movable each toward the other; springs, one individual to each follower, for resisting the approach of the followers toward each other; two interacting rockers, one rocker being fulcrumed upon each follower and actuatable thereby, said rockers being interposed between and engaged by said springs; and a floating roller structure interposed between said rockers.

4. A draft gear including a coupler; inner and outer followers actuated thereby and movable each toward the other; motion resisting elements, one individual to each follower, for resisting the approach of the followers toward each other; two interacting rockers, one rocker being fulcrumed upon each follower and actuatable thereby, said rockers being interposed between and engaged by said motion resisting elements; and a floating roller structure interposed between said rockers.

5. A draft gear including a coupler; inner and outer followers actuated thereby and movable each toward the other; springs,

one individual to each follower, for resisting the approach of the followers toward each other; two interacting rockers, one rocker being individual to each follower and actuatable thereby, said rockers being interposed between and engaged by said springs; and a floating hollow member between the rockers and into which opposing portions of the rockers project.

10 6. A draft gear including a coupler; inner and outer followers actuated thereby and movable each toward the other; motion resisting elements, one individual to each follower, for resisting the approach of the followers toward each other; two interacting rockers, one rocker being individual to each follower and actuatable thereby, said rockers being interposed between and engaged by said motion resisting elements; 15 and a floating hollow member between the rockers and into which opposing portions of the rockers project.

7. A draft gear including a coupler; inner and outer followers actuated thereby and movable each toward the other; springs, one individual to each follower, for resisting the approach of the followers toward each other; two interacting rockers, one rocker being fulcrumed upon each follower and 20 actuatable thereby, said rockers being interposed between and engaged by said springs; and a floating hollow member between the rockers and into which opposing portions of the rockers project.

30 8. A draft gear including a coupler; inner and outer followers actuated thereby and movable each toward the other; motion resisting elements, one individual to each follower, for resisting the approach of the followers toward each other; two interacting rockers, one rocker being fulcrumed upon each follower and 35 actuatable thereby, said rockers being interposed between and engaged by said springs; and a floating hollow member between the rockers and into which opposing portions of the rockers project.

40 9. A draft gear including a coupler; inner and outer followers actuated thereby and movable each toward the other; springs, one individual to each follower, for resisting the approach of the followers toward each other; two interacting rockers, one rocker being individual to each follower and 45 actuatable thereby, said rockers being interposed between and engaged by said springs; and a floating hollow member between the rockers and into which opposing portions of the rockers project. said floating member having a partition between the rockers and extending transversely of the gear; and a roller upon each side of said partition and interposed between the same and the corresponding rocker and having rolling engagement with this rocker.

sponding rocker and having rolling engagement with this rocker.

65

10. A draft gear including a coupler; inner and outer followers actuated thereby and movable each toward the other; motion resisting elements, one individual to each follower, for resisting the approach of the followers toward each other; two interacting rockers, one rocker being individual to each follower and actuatable thereby, said rockers being interposed between and engaged by said motion resisting elements; a 75 floating hollow member between the rockers and into which opposing portions of the rockers project, said floating member having a partition between the rockers and extending transversely of the gear; and a roller 80 upon each side of said partition and interposed between the same and the corresponding rocker and having rolling engagement with this rocker.

11. A draft gear including a coupler; inner and outer followers actuated thereby and movable each toward the other; springs, one individual to each follower, for resisting the approach of the followers toward each other; two interacting rockers, one 85 rocker being fulcrumed upon each follower and actuatable thereby, said rockers being interposed between and engaged by said springs; a floating hollow member between the rockers and into which opposing portions of the rockers project, said floating member having a partition between the rockers and extending transversely of the gear; and a roller upon each side of said partition and interposed between the same and the 90 corresponding rocker and having rolling engagement with this rocker.

12. A draft gear including a coupler; inner and outer followers actuated thereby and movable each toward the other; motion resisting elements, one individual to each follower, for resisting the approach of the followers toward each other; two interacting rockers, one rocker being fulcrumed upon each follower and 100 actuatable thereby, said rockers being interposed between and engaged by said motion resisting elements; a floating hollow member between the rockers and into which opposing portions of the rockers project, said floating member having a partition between the rockers and extending transversely of the gear; and a 105 roller upon each side of said partition and interposed between the same and the corresponding rocker and having rolling engagement with this rocker.

In witness whereof, I hereunto subscribe my name this eighteenth day of July, A. D. 110
1918.

HERMAN C. PRIEBE.
